ELECTRIC SHOE POLISHER CASE

William C. Badnaruk, Elverson, Pa., and Ira W. Schwartz,
Great Neck, N.Y., assignors to Schick Incorporated,
Lancaster, Pa., a corporation of Delaware

Filed July 2, 1962, Ser. No. 70,749

Term of patent 14 years

(Cl. D9—2)

Fig. 2.

Fig. 1.

Fig. 4.

Fig. 5.

Fig. 3.

FIG. 1 is a side elevational view of an electric shoe polisher case showing our new design;

FIG. 2 is a front elevational view thereof;

FIG. 3 is a rear elevational view thereof;

FIG. 4 is a top plan view; and

FIG. 5 is a bottom plan view.

The side not shown is substantially the same as the side shown.

The essential features of our design reside in the portions shown in solid lines in the drawings.

We claim:

The ornamental design for an electric shoe polisher case, substantially as shown and described.
